UNITED STATES PATENT OFFICE

HENRY L. LEWIS, OF STRATFORD, CONNECTICUT, ASSIGNOR TO THE H. J. LEWIS
OYSTER COMPANY, OF BRIDGEPORT, CONNECTICUT

OYSTER DREDGE

Application filed June 1, 1929. Serial No. 367,663.

This invention relates to oyster dredges, and particularly to improved means for supporting the oyster holding receptacle or bag and discharging its contents. It consists of 5 a bag holding attachment and its operating mechanism connected to the dredge, and in working relation with the rake, whereby the oysters are received and discharged at different points of the bag, and under the control 10 of a single operator. Where bags have but a single mouth both for receiving and discharging their contents, the dredge must be manually tilted to discharge, thus requiring the service of several hands.

15 In describing the invention in detail, reference will be had to the accompanying drawings wherein like characters of reference denote corresponding parts in the several views in which

20 Figure 1 represents an upper plan view of the dredge and broken view of a part of the bottom portion of the bag.

Figure 2 is a broken view of the bottom of the dredge looking in the direction of arrow 25 *a* of Figure 4.

Figure 3 is a side view of the dredge represented in operative position with the bag closed.

Figure 4 is a view of the dredge vertically 30 suspended with the bag opened to discharge its contents.

Figure 5 is a reduced diagrammatic view, looking in the direction of arrow *b* of Figure 1, of the oyster rake, and sectional view 35 of the lower rail of the frame on line *x*—*x* of Figure 1, and also a view of the drum shaft.

Figure 6 is a broken plan view of the skeleton frame of the dredge and its rake, also a 40 modified construction of means for controlling the bag operating mechanism.

Figure 7 represents outside winding drums and broken cables, and

Figure 8 is a broken view of the skeleton 45 frame of the dredge and the connecting means between the neck of the dredge and the winding drums.

The principal parts of the skeleton frame work of the dredge are of the conventional 50 type comprising the upper side rails 1, the

lower side rails 2 and braces 3, 4, 5, and 6. These rails and the center bar 7, Figure 1, terminate in a head formed by the neck portion 8 of the dredge. The oyster rake consists of the bar 9 and teeth 10, and is secured to the inner ends of the lower side rails 2 by means of the bolts 10^a. 55

11 is a drum supporting shaft journaled in the inner ends 1^a of the upper side rails 1, and also in the inner end of the center bar 7. 60 This shaft is rotated by means of the drum 12 about which is wound and to which is anchored the inner end of the main wire cable 13. The outer end of this cable passes freely through the upturned end 8^a of the neck of the dredge and is connected with any outside conventional major winding drum. 65

The stop 14 is so located on the cable that it will be brought against the upturned end 8^a of the neck in closing the flexible bag A. The 70 office of this stop is to take the pulling strain in hauling the dredge. The spring 14^a is interposed in the cable so that only enough strain is applied to the cable to close the bag and prevent undue strain on the bag operating mechanism. 75

The auxiliary side drums 15—15^a, on shaft 11, carry the wire cables 16, 17, anchored thereto and which extend therefrom over the pulleys 18, 19, rotatably mounted on the rod 20. The outer ends of these cables are finally anchored to the fixed collars 21, 22, on the rod 23. 24, 25, are end supporting bars whose inner ends are freely mounted on the shaft 11, and whose outer ends carry the pulley rod 80 20. The lateral arms 26, 27, form a part of the skeleton frame of the dredge and take the place of the conventional bow shaped ends of the ordinary dredge. The inner ends of these arms are anchored to the rake by the bolts 10^a, 85 and their outer ends are freely mounted on the shaft 11, and serve to support said shaft, as seen more clearly in Figure 5.

28, 29, are bag control levers whose outer ends carry the rod 23, and whose inner slotted ends have a sliding contact with the shaft 11. 30, 31, are links journaled on the rod 20 and the studs 32, 33, of the levers whereby said levers are maintained in workable relation with respect to the shaft 11 and the rods 90 100

20 and 23. 34, Figure 1, are simply interposed washers adapted to bring the inner faces of the links 30, 31, in alignment with the levers 28 and 29. 35, Figures 2, 3, 4, and 6, are brackets suspended from and near the ends of the rake bar as supports for the rod 36. Both brackets and rod form a part of the conventional dredge frame.

5 The oyster receptacle or bag A, seen more clearly in Figures 2, 3, and 4, is composed of the conventional chain links 37 forming the ends and bottom of the bag behind the rake. These bag links are conveniently attached to rods 23, 36, and arms 26, 27, and also to rods, one of which, 38 is mounted in the bracket 39, Figure 2, secured to the inner face of each of the levers 28, 29, but to avoid confusion it is only shown on the lever 29, seen more clearly in Figure 2. Any other suitable 10 means for connecting the bag to said levers could readily be devised.

15 The bag has the conventional and always open mouth adjacent the rake to receive the oysters gathered by the rake. In Figure 5 this open mouth is represented by B, bounded by the arms 26, 27, shaft 11, and the rake. Opposite this open mouth, I have provided a mouth through which the contents of the bag is discharged, a detail description of which 20 will later appear. The wire net work 40, Figure 1, serves as a cover to prevent an untimely discharge of the bag when closed. 41 are bars located between the drum shaft 11 and the pulley rod 20 and to which this net 25 work is attached as well as to the end supporting bars 24, 25.

42 is a bracket adjustably connected to the neck of the dredge carrying the trailing roller 43 by means of which the neck of the dredge 40 can be raised or lowered from the ground to change the cant or angle of the rake.

44 are braces secured to the supporting bars 24, 25, Figure 1, and also to the pulley rod 20 to give additional rigidity to said bars.

45, Figure 7, is a major winding drum rotatably mounted on the rod 46 and about which is wound the bag operating and dredge hauling cable 13. The drum 47 is also mounted on said rod to receive the cable 48 whose outer end is attached to the hook 49 and the latter to the link 50 swiveled to the neck of the dredge. Each of these drums has 50 an independent rotation on the rod 46 and may each be provided with tripping mechanism, not shown, to temporarily hold them against reverse rotation. These drums, and the means for rotating them to wind the cables, as well as other mechanism for operating them, are old and well known and form 55 no essential part of the present invention, but are simply shown as one of the many means that could be employed for the above described purpose.

60 The modified construction, shown in Figure 6, for controlling the bag operating

mechanism, consists of the two cables 51, 52, whose inner ends are attached to the lower end of the spring 14^a. These cables are then conducted through the guide links 53, 54, pivotally supported in the upper rails 1 of the dredge, and from thence are anchored to the rod 23, in the same manner as the independent cables 16, 17, shown in Figure 1.

65 This arrangement dispenses entirely with the drums 12, 15, and 15^a and converts the shaft 11 into simply the rod 11^a, Figure 6. The principal purpose of either shaft or rod is to provide means for supporting the several bag operating elements connected therewith.

70 The bag is closed and the dredge dragged along the bottom and hoisted aboard and suspended by means of the main cable 13. When in this suspended position, the weight of the dredge is shifted from the cable 13 to the cable 48, Figures 7 and 8. This shifting of the weight will permit the cable 13 to be slackened so that the accumulated weight of the bag's contents will force downward the slotted levers 28, 29, while the links 30, 31, will assist, in conjunction with pivotally supporting bars 24, 25, in forcing said levers back far enough to practically straighten the underside or bottom of the bag, Figure 4, and thereby automatically effect a free delivery of its contents through 75 the open discharge mouth C.

75 This lengthwise and swinging movement of the levers 28, 29, is an essential feature both in hauling and discharging, for when the bag is closed in hauling, it must necessarily assume a cup-like shape, Figure 3, to retain the oysters, and when released, is properly shaped to effect a free discharge. Were the levers simply swung from a pivot and without lengthwise movement, the bag 80 would practically retain its cup-like shape and more or less of the oysters would remain in the bag.

85 Several minor changes respecting the construction and arrangement of the operative elements of the dredge could be made without departing from the essential object and purpose of the invention, which relates principally to the bag construction whereby the oysters are received at one end of the bag, 90 and automatically discharged by gravity at the other end.

95 Having thus described my invention what I claim is:—

100 1. A dredge of the character described, comprising a frame, a rake carried by the frame, a flexible bag having an open receiving end supported on the frame adjacent the rake, a shaft journaled in the frame, a dredge hauling cable associated with the shaft, opposed levers mounted on the shaft having a lengthwise and swinging movement thereon, a rod connecting the outer 105 ends of the levers, the bag connected to the rod and levers to form a discharge opening.

for the bag, and auxiliary cables connecting the shaft and rod to close the bag through the medium of the dredge hauling cable.

2. A dredge according to claim 1, characterized by the fact that a stop is carried by hauling cable to engage a part of the frame to take the pulling strain in hauling the dredge, and a spring associated with said cable to prevent undue strain on the bag operating mechanism in closing the discharge opening of the bag.

3. In combination with a dredge frame and rake, a shaft journaled in the frame, a dredge hauling cable connected with the shaft, opposed levers mounted on the shaft and having a lengthwise and swinging movement thereon, a rod connecting the outer ends of the levers, a flexible bag having a normal open receiving end supported on the frame, and a discharge end engaging the levers and their connecting rod.

4. A dredge according to claim 3, characterized by the fact that bars are pivotally supported on the shaft and pivotally connected to the levers, a rod connecting the bars, auxiliary cables connecting the shaft with the lever mechanism, and pulleys on the rod for said cables.

5. In combination with a dredge frame, rake, and a dredge hauling cable, pivotally supported levers having a lengthwise swinging movement, cables for effecting said movement through the medium of the dredge hauling cable, a flexible bag having a normally open receiving end connected to the frame and adjacent to the rake, and a discharging end connected to said movable levers.

In testimony whereof I affix my signature.

HENRY L. LEWIS.
